UNITED STATES PATENT OFFICE.

EDWARD L. GONYER, OF MENDON, MICHIGAN.

DESIGN FOR A VEHICLE-BODY.

No. 38,963.

Specification for Design.

Patented Dec. 24, 1907.

Application filed October 11, 1907. Serial No. 397,030. Term of patent 14 years.

To all whom it may concern:

Be it known that I, EDWARD L. GONYER, a citizen of the United States, residing at the village of Mendon, county of St. Joseph, and State of Michigan, have invented a new, original, and ornamental Design for a Vehicle-Body.

My new, original and ornamental design for a vehicle body is clearly illustrated in the accompany drawing, in which

Figure 1 is a plan view and Fig. 2 is a side elevation thereof.

I claim

The ornamental design for a vehicle body, substantially as shown.

EDWARD L. GONYER.
